UNITED STATES PATENT OFFICE.

RENNALD A. PODRATZ, OF HARROLD, SOUTH DAKOTA, ASSIGNOR OF ONE-FOURTH TO
FORREST L. HUGHES, OF HARROLD, SOUTH DAKOTA.

DOOR-CLOSING DEVICE.

Application filed December 1, 1923. Serial No. 678,034.

To all whom it may concern:

Be it known that I, RENNALD A. PODRATZ, a citizen of the United States, residing at Harrold, in the county of Hughes and State 5 of South Dakota, have invented certain new and useful Improvements in Door-Closing Devices, of which the following is a specification, reference being had to the accompanying drawings.

10 This invention relates to door closing or checking devices, and particularly to those door closing devices in which a spring is used resisting the opening of the door but acting to urge the door to a closed position.

15 One of the objects of this invention is to provide a very simple device of this character which may be easily applied to barn, house or other doors and which is so constructed that after the door has been opened 20 and released it will cause the door to close quickly until the door is nearly closed and will then cause the relatively slower closing of the door, or which may be so adjusted that the door may be caused to close slowly 25 at first and then cause the quick and firm closing of the door.

A further object is to provide a device of this character by which the door may be held open at any desired position.

30 A still further object is to provide a device of this character which may be manually controlled so as to permit the door to close very readily if desired.

Another object is to provide a device of 35 this character which is so constructed that it may be accommodated to various exigencies of service.

Other objects will appear in the course of the following description.

40 My invention is illustrated in the accompanying drawings, wherein:—

Figure 1 is a fragmentary front elevation of a door casing and door with my door closer applied thereto;

45 Figure 2 is a top plan view of the construction illustrated in Figure 1, the door casing being in section;

Figure 3 is a longitudinal sectional view 50 through the cylinder 21 showing in elevation the piston, piston rod and allied parts;

Figure 4 is a vertical section through the casing 39;

Figure 5 is a fragmentary view of the up-

per portion of the cylinder with the petcock and the means for operating the petcock; 55

Figure 6 is an enlarged elevation of the means for locking the door in open position, the guide 24 and the door being in section;

Figure 7 is a fragmentary top plan view 60 of the arm 17 showing its connection to the shaft 14;

Figure 8 is a fragmentary sectional view 65 through the petcock and its supporting bracket showing the petcock closed.

Referring to these drawings, A designates a door as, for instance, a barn door of any ordinary and suitable construction and B the jamb or post of the door casing and to which the door is hinged by the hinges C. 70

Attached to the door jamb or door casing at the hinged end of the door in any suitable manner is a plate 10 which has outwardly projecting ears 11 and the face of this plate is provided with the outwardly projecting ear 12 and an outwardly projecting ear 13. The projecting ear or lug 12 has an opening through it for the passage of a rock 75 shaft 14. The ear 13 has a hole 15 cut in it for the passage of the shaft 14, and the lower 80 end of the plate 10 is formed with an outwardly projecting lug 16 which forms a platform or shelf upon which the lower end of the shaft 14 sets and rotates, the lower end of this shaft 14 having a head 14^a resting 85 upon this shelf. The upper end of the shaft 14 has attached to it to oscillate with it in a manner hereafter described an arm 17 which extends parallel to the door when 90 the door is closed, the outer end of this arm being angularly bent. Surrounding this shaft 14 is a coiled torsion spring 18 attached at one end to the plate 10, as at 19, and at the other end to the shaft, as at 19^a. Preferably this arm is angularly bent so that 95 that portion of the arm adjacent the shaft 14 will be in line with the axis of the cylinder 21.

Attached to the face of the door A is a plate 20 which carries upon it a cylinder 100 21, this cylinder being closed at that end adjacent the hinge of the door. Operating within this cylinder 21 is a piston 22 carried by a piston rod 23. This piston is connected to the angular end of arm 18. The end 105 of the rod 23 passes through a guide 24.

The closed end of the cylinder is provided with an inlet valve 25 of any suitable construction which is urged to a closed position by a light spring, but as the piston moves outward through the cylinder 21 or away from the hinged edge of the door the piston will suck air in through the opening 25. The cylinder has an air outlet opening 26 which communicates with the exterior air through a petcock 27 which may be of any suitable or ordinary form provided with the usual valve 28, this valve having an arm 29.

Mounted in guides 30 and 31 is a reciprocatable rod 32 whose end may be caused to approximate the arm 29 so as to shift the petcock. This rod 32 extends through the guides 30 and 31 and is then bent to engage with the plunger rod 23. Thus as the plunger moves into the cylinder, the rod 32 will shift through its guides and strike the arm 29 and shift the valve of the petcock to a fully closed position. A spring 33 urges the petcock to a position where it is nearly or fully open and an adjustable stop 34 is provided whereby to control the degree to which the petcock will move under the action of the spring.

With this construction it will be obvious that as the door is opened the spring 18 will be caused to contract. As the door opens, the plunger rod 23 moves through its guides and the piston is drawn away from the closed end of the cylinder. As the piston moves away from the closed end of the cylinder, the valve 25 and the petcock will open to permit the inlet of air. When the door is released after having been opened, the spring 18 urges the door to a closed position and as the door closes, the piston will move toward the closed end of the cylinder. The air cannot escape through the valve 25 and the only way for the air to escape is through the relatively small aperture of the petcock valve. Therefore, this air which is between the piston and the closed end of the cylinder will somewhat check the closing movement of the door. When the door is very nearly closed, however, the rod 32 will strike the arm 29 of the petcock or any other part that is connected therewith and this will turn the valve 28 to a nearly closed position and then the spring will act to shift the door to its fully closed position.

The petcock is preferably provided with a thumb piece 35 whereby the petcock may be operated by hand so that if at any time it be desired to cause the full closing of the door either from the front of the door or from the back of the door, the petcock may be fully opened. This will permit the door to be shifted quickly to its fully open position against the action of the spring 18 or to cause the door to close quickly or slam.

For the purpose of holding the door in a partially open position, I may provide the plunger rod 32, which plunger rod is preferably rectangular or square in cross section, with a series of notches 36, and provide a latch of any suitable character mounted in the guide 24 for the rod. I have illustrated for this purpose a latch consisting of a spring actuated bolt which engages the notches 36 but which may be retracted by means of a cord 38 engaged with the lever 38^a, which in turn is engaged with a bolt. The bolt may be held out of engagement with the notches 36 by means of the set screw 36^a whenever desired. The cord 38, as illustrated in Figure 1, may pass down the door frame and then extend outside or through the door frame to an operating handle so that the latch may be withdrawn from the inside and outside of the door. By turning the set screw 36^a, the bolt may be held permanently withdrawn. By means of the bolt the door may be held open to any desired angle.

Preferably the plate 10 will be provided with a cover 39 having ears 40 aligning with the ears 11 and through which bolts may pass to hold the cover closed upon the plate and thus protect the spring 18 and allied parts from the elements. Preferably the arm 19 will be attached to the upper end of the rod 14 by forming this rod with a head 41. The arm 18 has a head 42 which embraces the head 41 and the confronting or contacting faces of the two rods will be formed with a plurality of longitudinally extending openings 43 into which a screw may be placed and thus the arm 19 may be adjusted to any angular position with relation to the axis of the rod 14.

It will be obvious that with this construction the shaft 14 might be disposed with its head 41 downward to engage the arm 19, or the arm 19 might be disposed above the plunger rod 23 and the plate 10 be mounted so that the headed end 41 of the shaft 14 is downward or upward, whichever is most desirable. In other words, all of these parts may be readily adjusted to suit exigencies of operation and construction.

While preferably the petcock 27 is so arranged that it is normally open, as illustrated in Figure 3, permitting the quick movement of the piston inward and the quick closing of the door up to a certain point and then the slow closing of the door due to the turning of the petcock from the position shown in Figure 3 to that shown in Figure 8, it will be obvious that the petcock might be differently adjusted so as to be partially closed while the piston was moving toward the petcock and then be shifted to a fully open position by the rod 32 when the piston 22 had arrived nearly at the

end of the cylinder. It is obvious that this is a mere matter of adjustment and that, therefore, my mechanism is capable of use in either way.

5 1. I claim:—

10 1. A door closer comprising a supporting member adapted to be attached to the door casing, a shaft mounted in the supporting member, a spring resisting rotation of the shaft in one direction, a supporting member mounted on the door, a cylinder thereon having an inlet and an outlet opening, a piston operating in the cylinder and having a piston rod, an arm attached to the shaft and extending across the door and pivotally engaged with the piston rod, an inwardly opening valve controlling inlet to the cylinder, a valve controlling outlet from the cylinder and yieldingly held in a partially open position, and means controlled by the piston rod for fully opening said valve as the piston rod nears the end of the cylinder having inlet and outlet openings and as the door nears its closed position.

25 2. A door closer comprising a supporting member adapted to be attached to the door casing, a shaft supported thereby, a spring resisting rotation of the shaft in one direction, a supporting member adapted to be mounted on the door, a cylinder thereon having an inlet and an outlet opening at one end, a piston operating in the cylinder and having a piston rod, an arm attached to the shaft adapted to extend across the hinged portion of the door and having pivotal engagement with the piston rod, an inwardly opening valve controlling inlet of air to the cylinder, a valve controlling outlet and yieldingly held in a partially open position, and a member shiftable with the piston rod and adapted as the piston nears the valved end of the cylinder and the door is nearly closed to engage said outlet valve and fully open it.

35 3. A door closer comprising a supporting member adapted to be attached to a door casing, a shaft supported thereby and adapted to extend parallel to the side of the door, a spring coiled around the shaft and attached to said supporting member and yieldingly resisting rotation of the shaft in a direction to open the door, a supporting member adapted to be mounted on the door and having a cylinder thereon, the cylinder being formed with an inlet and an outlet opening at one end, a piston operating therein and having a piston rod, an arm attached to said shaft and adapted to extend transversely across the hinged margin of the door and pivotally engaged with the piston rod, an inwardly opening valve controlling inlet of air to said cylinder, a valve controlling the outlet therefrom and yieldingly held in a partially open position, means for manually opening the valve, and means actuated by said piston rod operatively engaging the valve as the piston nears that end of the cylinder having the inlet and outlet openings, and means engaging with the piston for latching it in a position with the piston more or less withdrawn from the inlet end of the cylinder whereby to latch the door in a partially opened position.

40 4. A door closer comprising a supporting member adapted to be attached to a door casing, a shaft supported thereby and adapted to extend parallel to the side of the door, a spring coiled around the shaft and attached to said supporting member and yieldingly resisting rotation of the shaft in a direction to open the door, a supporting member adapted to be mounted on the door and having a cylinder thereon, the cylinder being formed with an inlet and an outlet opening at one end, a piston operating therein and having a piston rod, an arm attached to said shaft and adapted to extend transversely across the hinged margin of the door and pivotally engaged with the piston rod, an inwardly opening valve controlling inlet of air to said cylinder, a valve controlling the outlet therefrom and yieldingly held in a partially open position, means for manually opening the valve, and means actuated by said piston rod operatively engaging the valve as the piston nears that end of the cylinder having the inlet and outlet openings, and means engaging with the piston for latching it in a position with the piston more or less withdrawn from the inlet end of the cylinder whereby to latch the door in a partially opened position.

45 5. A door closer comprising a supporting member adapted to be attached to a door casing, a shaft supported thereby and adapted to extend parallel to the side of the door, a spring coiled around the shaft and attached to said supporting member and yieldingly resisting rotation of the shaft in a direction to open the door, a supporting member adapted to be mounted on the door and having a cylinder thereon, the cylinder being formed with an inlet and an outlet opening at one end, a piston operating therein and having a piston rod, an arm attached to said shaft and adapted to extend transversely across the hinged margin of the door and pivotally engaged with the piston rod, an inwardly opening valve controlling inlet of air to said cylinder, a valve controlling the outlet therefrom and yieldingly held in a partially open position, means for manually opening the valve, and means actuated by said piston rod operatively engaging the valve as the piston nears that end of the cylinder having the inlet and outlet openings, and means comprising a rod attached to and movable with the piston rod and extending parallel thereto.

50 6. A door closer comprising a supporting member adapted to be attached to a door casing, a shaft supported thereby and adapted to extend parallel to the side of the door, a spring coiled around the shaft and attached to said supporting member and yieldingly resisting rotation of the shaft in a direction to open the door, a supporting member adapted to be mounted on the door and having a cylinder thereon, the cylinder being formed with an inlet and an outlet opening at one end, a piston operating therein and having a piston rod, an arm attached to said shaft and adapted to extend transversely across the hinged margin of the door and pivotally engaged with the piston rod, an inwardly opening valve controlling inlet of air to said cylinder, a valve controlling the outlet therefrom and yieldingly held in a partially open position, means for manually opening the valve, and means actuated by said piston rod operatively engaging the valve as the piston nears that end of the cylinder having the inlet and outlet openings, and means engaging with the piston for latching it in a position with the piston more or less withdrawn from the inlet end of the cylinder whereby to latch the door in a partially opened position.

55 7. A door closer comprising a supporting member adapted to be attached to a door casing, a shaft supported thereby and adapted to extend parallel to the side of the door, a spring coiled around the shaft and attached to said supporting member and yieldingly resisting rotation of the shaft in a direction to open the door, a supporting member adapted to be mounted on the door and having a cylinder thereon, the cylinder being formed with an inlet and an outlet opening at one end, a piston operating therein and having a piston rod, an arm attached to said shaft and adapted to extend transversely across the hinged margin of the door and pivotally engaged with the piston rod, an inwardly opening valve controlling inlet of air to said cylinder, a valve controlling the outlet therefrom and yieldingly held in a partially open position, means for manually opening the valve, and means actuated by said piston rod operatively engaging the valve as the piston nears that end of the cylinder having the inlet and outlet openings, and means comprising a rod attached to and movable with the piston rod and extending parallel thereto.

and attached to said supporting member and yieldingly resisting rotation of the shaft in a direction to open the door, a supporting member adapted to be mounted 5 on the door and having a cylinder thereon, the cylinder being formed with an inlet and an outlet opening at one end, a piston operating therein and having a piston rod, an arm attached to said shaft and 10 adapted to extend transversely across the hinged margin of the door and pivotally engaged with the piston rod, an inwardly opening valve controlling inlet of air to said cylinder, a valve controlling the outlet therefrom and yieldingly held in a partially open position, means for manually opening the valve, means actuated by said piston rod operatively engaging the valve as the piston nears that end of the cylinder having the inlet and outlet 15 openings, means engaging with the piston for latching it in a position with the piston more or less withdrawn from the inlet end of the cylinder whereby to latch the door in a partially opened position, said means comprising notches on the piston rod, and a manually actuated latch mounted upon the supporting member and adapted to engage said notches.

7. A door closer comprising a supporting member adapted to be attached to a door casing and having outwardly projecting ears, one above the other, the lowermost ear being slotted inward toward the plate, a shaft passing through the openings in the ears, a lug formed upon the plate below the end of the shaft and upon which the lower end of the shaft rests and rotates, a coiled spring attached at one end to the plate and at the other end to the shaft and acting to resist the rotation of the shaft in one direction, an arm mounted upon the shaft for angular adjustment around the shaft, a plate adapted to be mounted upon the face of the door and having an air chamber, that end of the air chamber adjacent the hinge of the door having means for admitting air and permitting the escape of air, the last named means including a valve, a piston operating within the air chamber and having a piston rod, the arm extending from the shaft being angularly bent and pivotally engaged with said rod, and means for closing said valve automatically as the piston nears the outlet and inlet end of the air chamber and the door approximates its closed position comprising a rod mounted in guides and having operative engagement with the piston rod and adapted to engage said valve to close it when the piston has neared the outlet and inlet end of the air chamber.

8. A door closer comprising a support-

ing member adapted to be attached to a door casing, a shaft mounted in the supporting member, a spring resisting rotation of the shaft in one direction, a supporting member mounted on the door, a cylinder thereon having an inlet and an outlet opening, a piston operating in the cylinder and having a piston rod, an arm attached to the shaft and extending across the door and pivotally engaged with the piston rod, an inwardly opening valve controlling inlet from the cylinder, a valve controlling outlet from the cylinder and yieldingly held in a vertical position, means for fully opening said valve as the piston rod nears the end of the cylinder having inlet and outlet openings and as the door nears its closed position, a spring actuated latch adapted to engage the piston rod and hold it from movement, manually operable means for temporarily withdrawing said latch and to permit the operation of the piston rod, and means for locking the latch out of engagement with the piston rod to permit the free movement of the piston rod.

9. A door closer including a cylinder, a piston operating within the cylinder, the cylinder being adapted to be mounted upon a door, means connected to the door casing and to the piston to cause the movement of the piston in one direction through the cylinder upon the opening of the door and the movement of the piston in the other direction upon the closing of the door, a petcock carried at one end of the cylinder, a spring holding the petcock in a normal position, and means moving with the piston and carried thereby adapted to engage the petcock as the piston nears the petcock end of the cylinder to cause the movement of the petcock in one direction, and a spring acting to urge the door to a closed position.

10. A door closing mechanism including a cylinder adapted to be mounted upon the door and having a piston and a piston rod operating therein, a spring adapted to be mounted upon the door casing and having an arm engageable with the piston rod to thereby cause the movement of the piston in one direction as the door is opened and the movement of the piston in the other direction as it is closed, a petcock mounted upon one end of the cylinder and having a rotatable valve having an arm projecting therefrom, and a rod operatively connected to the piston and moving therewith, said rod as the piston nears one end of the cylinder engaging the arm of the petcock to shift the petcock.

In testimony whereof I hereunto affix my signature.

RENNALD A. PODRATZ.
